UNITED STATES PATENT OFFICE.

FREDERIC E. STURDY, OF ATTLEBOROUGH, MASSACHUSETTS, ASSIGNOR TO
J. F. STURDY'S SONS, OF SAME PLACE.

DESIGN FOR A WATCH-CHAIN.

SPECIFICATION forming part of Design No. 25,557, dated June 2, 1896.

Application filed April 9, 1896. Serial No. 586,878. Term of patent 7 years.

To all whom it may concern:

Be it known that I, FREDERIC E. STURDY, a citizen of the United States, residing at Attleborough, in the county of Bristol and State of Massachusetts, have invented and produced a new and original Design for Watch-Chains; and I hereby declare that the following is a full, clear, and exact description of the same, reference being had to the accompanying drawing, forming part of this specification.

The drawing is a view of a watch-chain, showing my design.

The characteristic features of my design consist in the main portion of the chain having the appearance of a sprocket-chain, the connecting-links at the ends, and the pendant.

In the drawing, *a* indicates the usual form of watch-swivel, secured to one end of the watch-chain; *b*, an end link of cylindrical

cross-section, having a ring projecting from one side.

c c indicate the intermediate links, rounded at the ends *e e*, united by the flat surfaces *f*. 25 The bars *d d*, slightly curved, extend from the links *b b* to the adjacent links *c c* and in the body of the chain from each side of the links *c c* to the adjacent links *e e*. From the free end of the chain a pendant *g*, having the conventional form of a lantern, is suspended. 30

Having thus described my newly-designed watch-chain, I claim as new and desire to secure by Letters Patent—

The design for a watch-chain herein shown 35 and described.

In witness whereof I have hereunto set my hand.

FREDERIC E. STURDY.
